ANDREAS P. LUNDIN, OF BAYSIDE, NEW YORK, ASSIGNOR TO WELIN MARINE EQUIPMENT COMPANY, A CORPORATION OF NEW YORK.

BOAT.

1,140,469.

Specification of Letters Patent. Patented May 25, 1915.

Application filed May 1, 1912. Serial No. 694,432.

To all whom it may concern:

Be it known that I, ANDREAS P. LUNDIN, a citizen of the United States, and a resident of Bayside, borough of Queens, county 5 of Queens, and State of New York, have invented certain new and useful Improvements in Boats, of which the following is a specification.

This invention relates to improvements in 10 boats, particularly adapted for use as life-boats.

By the use of my invention two or more similar shaped efficient life-boats of increased stability and buoyancy, and of substantially 15 as great seating capacity as the ordinary non-stowable life-boat, may be readily stowed one on top of the other; the topmost boat will be capable of being loaded without preliminary adjustment or change of form; 20 all parts of canvas or other similar flexible material heretofore used in collapsible life-boats and which has proven unsatisfactory is eliminated, the only adjustments being of rigid parts for the purpose of attaining ad- 25 ditional security and to permit the rowing or sailing of the boat; and such adjustments may be made substantially instantaneously and either while the boat is being loaded or during the lowering process, or while it is in 30 the water or at any other suitable time.

The preferred form of my invention comprises a metallic shell having a substantially flat bottom and a well of oblong box-shape configuration, the sides of which well are 35 reinforced and kept rigid by the usual marginal and cross seats and in any other well known way; a series of air-tight chambers or compartments between the bottom of the boat or shell and the bottom of the well, sepa- 40 rated by vertical dividing partitions and the top of such air-chambers which forms the bottom of the well and the floor of the boat being located above the water-line; when the boat is loaded to its full capacity; a series of 45 bailing tubes communicating with the floor of the boat and its bottom, each tube having a reduced opening at its upper end and being provided at such upper end with a valve in the form of a rubber ball adapted to close 50 or seat on such reduced opening to keep out water but to open to permit water to escape from the well; a superstructure comprising rigid side and end members or leaves hinged to the shell-plating and adapted to fold in- 55 wardly, the line of folding or hinging being

substantially coincident or in the same horizontal plane as the upper surface of the marginal and cross seats, and means comprising a series of slotted and notched lock plates co-operating with locking rods attached at one 60 end to the side and end members or leaves respectively, and having the other end bent to reciprocate in the slot when the side and end members are raised or lowered and to spring into and lock with the locking notches 65 when such members are forced slightly beyond their normal vertical positions. I also preferably provide what I shall term supplementary buoyant sides of balsa wood which are connected to the flat sides of the 70 metallic shell in any suitable manner and round out the symmetrical contour of the boat.

In the accompanying drawings, in which similar reference characters designate corresponding parts throughout the several views, Figure 1 is a side elevation of a life-boat embodying my invention and showing the superstructure folded down; Fig. 2 is a plan view of the boat shown in Fig. 1, the superstructure being locked in upright or vertical position; Fig. 3 is a section taken through the longitudinal axis of the boat showing the superstructure locked in upright or vertical position; Fig. 4 is a side elevation of 85 two life-boats embodying my invention, one stowed on top of the other; and Fig. 5 is an enlarged cross-section of my improved life-boat, the position of the second boat being shown in dotted lines.

Referring now to the accompanying drawings which illustrate a preferred embodiment of my invention, A designates a shell of metal or other suitable material having a substantially flat bottom a and provided with a well or cockpit B, the space between the bottom a and the floor b of the well B being divided into a series of air-tight compartments or chambers C by suitable dividing partitions c. As illustrated, the well B is 95 rectangular in configuration and is provided at the extreme upper edge with cross seats E and marginal seats F which, together with the metallic flow of the well, assist in reinforcing the shell to form a structure of great 100 strength and rigidity. A series of suitable tubes D preferably connect openings in the floor of the well and the bottom of the boat. The communicating opening between each 105 of these tubes and the floor b is preferably 110

of reduced diameter and a valve comprising a floating or buoyant rubber ball of larger diameter than said reduced opening is loosely retained in the upper end of the tube 5 by means of a pin d' so that water within the well may be permitted to escape therefrom, but when water within the tube rises sufficiently high as to normally enter the well, the valve d will close the reduced aperture 10 and prevent such entrance of water. If desired, the shell A may be further reinforced or stiffened in any well known manner without interfering with the folding of the superstructure as hereinafter described.

15 A protective superstructure, comprising rigid side members G and end members G', is connected to the shell plating at the sides and ends of the rectangular well and is adapted to be raised and lowered relatively to 20 the shell. Obviously when the side and end members G G' are raised relatively to the shell, they form a superstructure which will prevent the boat from being flooded with water and will protect the occupants thereof from wind, waves and spray in rough 25 weather, and when such side and end members G G' are lowered relatively to the shell a plurality of such boats may be readily stowed or nested one on top of the other on 30 board ship and under davits. As illustrated, the side members G and end members G' are hinged by means of hinges g^3 to the shell plating and are adapted to be folded inwardly and to rest on the seats of the boat 35 when the boats are not in use and it is desired to stow the same one on top of the other. Means for automatically locking the side and end members when the same are moved into vertical position is preferably 40 provided, such means preferably comprising a series of lock plates g' , the plates for the side members G being secured to the sides of the cross seats E and the plates for the end members G' being secured to the 45 sides of the marginal or side seats F. Each lock plate g' is provided with a horizontal slot g^6 and a locking notch g^2 ; a locking rod g is connected at one end with the upper edge of one of the members G G' and its 50 other end is provided with a bent portion which extends within and is adapted to reciprocate in such slot g^6 during the raising and lowering of the members G G', and to lock with the locking notch g^2 which extends 55 downwardly and rearwardly from the end of the slot g^6 nearest to the members G G', so that when a member G or G' is raised to its extreme upright or vertical position and then sprung back slightly beyond its normal 60 vertical position, the bent portion of the rod will spring into the locking notch and the member G or G', as the case may be, will be securely and automatically locked in vertical or upright position. I also prefer- 65 ably provide each of the members G G'

with a stiffening rib g^5 which, when such members are in vertical position, tend to reinforce the same but when such members are in their folded or lying down position the ribs g^5 serve as a somewhat elevated support or cradle for stowing another similar boat on top thereof and leave room between the seats of one boat and the bottom of the next to stow oars, masts, swords and other accessories.

75 Another feature of my invention is the provision of a rigid metallic shell having flat sides with what I shall term "supplementary sides" of highly buoyant material and preferably of balsa wood. I preferably 80 so form such supplementary sides as to round out the contour of the boat. These supplementary sides may be secured to the metallic shell plate by lashing the same to the sides of the metallic shell or in any other 85 suitable manner, and will not only materially add to the strength and stability of the lifeboat but will serve as fenders or guards to prevent injury to the boat in the event that it be bumped against the vessel 90 in launching. Balsa wood when properly treated to close its pores is highly buoyant and will have substantially the same degree of buoyancy as would for instance metallic 95 air-tight compartments of the same size, and furthermore in view of the fact that these supplementary sides do not form an integral part of the hull proper they may be ground to pieces or entirely destroyed by impact with the sides of the vessel without 100 injuring the water-tight qualities of the boat.

I furthermore preferably provide my improved boat with any well known disengaging gear such as I have designated K, a manhole for drinking water and supplies, 105 which I have designated L, and the upper edges of the side members G are provided with oar-locks or notches g^4 to permit the rowing of the boat. I also preferably provide removable lee-boards or swords I, 110 which act as means for permitting the boat to be properly handled when it is desired to step a mast therein and sail it.

Having described my invention, I claim:

1. A lifeboat comprising a metallic shell 115 having a well, polygonal in conformation, air-tight compartments beneath the well, marginal and cross seats connected to the shell at the upper edge of the well, a superstructure composed of rigid side and end 120 members hinged to the shell and adapted to fold inwardly and means for automatically locking such side and end members when the same are moved into raised position.

2. A boat comprising a rigid metallic shell 125 comprising rounded fore and aft sections and an amidship section having a well polygonal in conformation, provided with seats and having flat outer sides, supplementary sides of highly buoyant material 130

- connected to the amidship section outer sides of the metallic shell to round out the contour of the boat, add to its stability and serve as fenders.
5. 3. A lifeboat comprising a metallic shell having a well, polygonal in conformation, air-tight compartments beneath the well, marginal and cross seats connected to the shell at the upper edge of the well, a superstructure composed of side and end members hinged to the shell and adapted to fold inwardly, a stiffening rib on each side and end members for reinforcing the same when in raised position and serving as an elevated support for another boat when in folded position, and means for automatically locking such side and end members when the same are moved into raised position.
4. A boat embodying a rigid metallic shell comprising rounded fore and aft sections and an amidship section provided with a well polygonal in conformation and having flat sides, and supplementary sides composed of balsa wood having its pores closed against the admission of water and attached to said flat outer sides to round out the contour of the boat, add to its stability and serve as fenders.
5. A lifeboat embodying therein a metallic shell having a well polygonal in conformation, air tight compartments beneath the well, a superstructure composed of side and end members each of which is rigid over its entire surface and is hinged to the shell to permit raising and lowering thereof and means for automatically locking such side and end members when the same are moved into raised position.
- In witness whereof, I have signed my name to the foregoing specification in the presence of two subscribing witnesses.

ANDREAS P. LUNDIN.
